(57) **CLAIM**

The ornamental design for a duty belt, as shown and described.

DESCRIPTION

FIG. 1 is a front perspective view of a duty belt, showing our new design in a fastened configuration;

FIG. 2 is a rear perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1;

FIG. 8 is a bottom plan view of FIG. 1;

FIG. 9 is a front elevational view thereof, illustrated in a flat, unfastened configuration; and,

FIG. 10 is a rear elevational view of FIG. 9.

The broken lines in the figures depict stitching, and do form part of the claimed design.
